UNITED STATES PATENT OFFICE.

DANIEL GIESE, OF PEORIA, ILLINOIS.

COAL-DRILL.

SPECIFICATION forming part of Letters Patent No. 406,040, dated July 2, 1889.

Application filed April 14, 1888. Serial No. 270,644. (No model.)

To all whom it may concern:

Be it known that I, DANIEL GIESE, a citizen of the United States, residing at Peoria, in the county of Peoria and State of Illinois, have invented certain new and useful Improvements in Coal-Drills; and I do hereby declare that the following is a full, clear, and exact description of the invention, which will enable others skilled in the art to which it applies to make and use the same.

My invention relates to drilling-machines; and it consists in the construction and combination of devices and parts hereinafter described and set forth, whereby a simple, efficient, and durable drilling-machine is provided that is composed of comparatively but few parts, which, when in use, will occupy but little space, and in addition permit the ready application and removal of the drill-stock.

In the accompanying drawings, forming part of this specification, Figure 1 is a perspective view of a drilling-machine embodying my improvements. Fig. 2 is an inverted plan view showing in enlarged detail the pivoted body, and Fig. 3 is a front view of Fig. 2.

The main bracket of the machine comprises a horizontal portion *a* and side standards *b*, each of the latter being recessed at its upper edge to form half of a bearing. A bolt *c* depends centrally from the portion *a*, and has swiveled thereon a looped end *d* of a horizontal brace *A*, composed of a bar twisted at its end to form the loop and then spread to form the diverging members *e e'*, which are pointed at their ends to positively engage any surface with which they may contact, and having spurs *f* to prevent too deep a penetration.

The frame or body in which the drill-stock bears and travels is composed of two sections *B C*, the former being provided at its lower portion with ears *g*, which bear against the ends of the lower cylindrical portion of the section *C*, and have openings which align with an opening in said portion *h* to admit of the passage of a bolt *i*, for pivotally connecting the lower portions of said sections *B C* together. The central part of each section *B C* has a longitudinally-extending recess semi-circular in form and located on its inner side. Each of said recesses is internally threaded, so that when said sections are brought to-

gether they conjointly form a threaded opening *j*, in which the tool-stock bears and travels. The top part of the section *B* is provided with a rectangular integral block *k*, which, when the sections *B C* are brought together, is adapted to be embraced by a flange *l* on the section *C*, and connected thereto by means of bolts *m*, passing through the end walls of said flange and engaging threaded openings in said block. Each section *B C* has horizontally extending from its side a transverse trunnion *n*, designed to bear in the recess in the upper end of the adjacent standard *b*, and be retained therein by means of a cap *o*, detachably secured to said standard by suitable bolt devices.

A bevel gear-wheel *D* has its hub portion *p* seated in a recess or depression *q*, formed at the mouth of the opening *j*, and the section *C* has integrally a lateral and forwardly-extending arm *E*, which carries at its end a small transverse cylinder *F*, having a transverse perforation, in which bears a shaft carrying at its inner end a beveled wheel *G*, meshing with the wheel *D*, while the outer end of said shaft carries an operating-crank *H*.

I refers to the extended drill-stock, which is threaded throughout its surface to engage the threaded opening *j*, and is also provided with an extended keyway *r*, which is engaged by a spline on the gear-wheel *D*.

In operation the brace *A* is turned so as to secure a bearing against some suitable portion, and the tool or drill *J* is fitted in the socket *s* at the front end of the stock. Now, by rotating the gear-wheel *G*, the wheel *D* is caused to rotate, and by its spline and keyway-connection with the stock rapidly rotates the latter, so that it, through its threaded engagement with the opening *j*, is caused to advance or recede, according to the direction of rotation.

It will be noticed that the strain necessary to forwardly feed the stock is in no way experienced by the gear-wheel *D*, but is sustained by the portion or part best calculated to withstand it—to wit, the body formed of the sections *B C*. Another important advantage connected with my improvement consists in the fact that the sections *B C* may be readily swung apart for the application or removal

of the bit-stock, which can be engaged or disengaged from the wheel D by simply sliding the latter longitudinally onto or from said stock.

5 I claim—

In a coal-drill, the combination, with the bracket having a pivot-bolt, of the brace having its members twisted into a loop or eye at their inner ends, which receives said bolt, the 10 outer portions of said members diverging from

each other and having laterally-projecting spurs or projections, substantially as and for the purpose set forth.

In testimony whereof I affix my signature in presence of two witnesses.

DANIEL GIESE.
